US0D1011031S

(12) **United States Design Patent** (10) **Patent No.:** **US D1,011,031 S**
(45) **Date of Patent:** **** Jan. 16, 2024**

(54) **WALLET**

(71) Applicant: **The Ridge Wallet LLC**, Santa Monica, CA (US)

(72) Inventor: **Daniel Kane**, Agoura Hills, CA (US)

(73) Assignee: **The Ridge Wallet LLC**, Santa Monica, CA (US)

(**) Term: **15 Years**

(21) Appl. No.: **29/813,624**

(22) Filed: **Oct. 29, 2021**

Related U.S. Application Data

(63) Continuation of application No. 17/035,261, filed on Sep. 28, 2020, now Pat. No. 11,596,212, which is a continuation of application No. 15/421,596, filed on Feb. 1, 2017, now Pat. No. 10,791,808, which is a continuation-in-part of application No. 14/706,019, filed on May 7, 2015, now abandoned.

(57) **CLAIM**

The ornamental design for a wallet, as shown and described.

DESCRIPTION

FIG. 1 is a front perspective view of a wallet;

FIG. 2 is a side perspective view illustrating the wallet in an open configuration;

FIG. 3 is a front view of the wallet shown in the closed configuration of FIG. 1;

FIG. 4 is a rear view thereof;

FIG. 5 is a bottom view thereof;

FIG. 6 is a top view thereof;

FIG. 7 is a right side view thereof;

FIG. 8 is a left side view thereof; and,

FIG. 9 is an exploded perspective view thereof.

The broken lines showing cards inserted into the wallet are for the purpose of illustrating environmental structure and form no part of the claimed design.

1 Claim, 6 Drawing Sheets
